UNITED STATES PATENT OFFICE.

EDWARD H. WIERSCHING AND EDWARD K. WIERSCHING, OF BINGHAMTON, NEW YORK.

DESIGN FOR A TOOTHBRUSH-CASING.

55,143.

Specification for Design.

Patented May 11, 1920.

Application filed May 24, 1919. Serial No. 299,674. Term of patent 7 years.

To all whom it may concern:

Be it known that we, EDWARD H. WIERSCHING and EDWARD K. WIERSCHING, citizens of the United States, residing at Binghamton, in the county of Broome and State of New York, have invented a new, original, and ornamental Design for a Toothbrush-Casing, of which the following is a specification, reference being had to the accompanying drawing forming part thereof.

The figure is a side elevational view of a toothbrush casing, showing our new design. We claim:

The ornamental design for a toothbrush casing, as shown.

EDWARD H. WIERSCHING.
EDWARD K. WIERSCHING.
